UNITED STATES PATENT OFFICE.

EARL S. TEED, OF AKRON, OHIO, ASSIGNOR TO THE TEXTILE RUBBER COMPANY, OF AKRON, OHIO, A CORPORATION OF OHIO.

APPARATUS FOR DRYING ARTIFICIAL SILK, YARN, OR THE LIKE.

Application filed March 20, 1926. Serial No. 96,359.

This invention relates to a new and improved apparatus for use particularly in drying skeins of artificial silk, hanks of yarn in dyeing operations, and for other and analogous purposes.

The objects of the invention are to improve upon existing structures for this purpose, to obtain more satisfactory results and to improve the character of the product obtained. It is also a purpose of the invention to avoid certain disadvantages connected with the use of former types of apparatus.

The invention has for its purpose the construction of an improved pole which is used for the support of skeins of artificial silk known in the trade as "rayon" during the drying. It is also for use in the dyeing industry for the support of hanks of yarn while drying. The invention is, therefore, in a construction of a "dye pole," as it is known in the trade, although its use is not necessarily so limited but may be extended to other fields and arts.

Dye poles of the prior art have been made either of wood or glass. The first form of pole is unsatisfactory for many reasons, principally due to the chipping of the poles and the fact that fragments of wood will be caught in the hanks of yarn. Wooden poles are also unsatisfactory because of the fact that they become stained and will discolor delicate yarns and threads and are therefore unsuitable for some of the higher grades of work. Glass poles are expensive and fragile and, in addition, will chip easily, the sharp edges causing the yarns or threads to be cut.

The improved form of pole shown herein overcomes the disadvantages and difficulties attendant upon the use of wooden or glass poles, and has many advantages over the prior forms of poles in long life and greater usefulness.

In the drawings is shown one form of the invention only, it being understood that changes and modifications may be made in specific embodiments of the invention. After the invention has been described and explained to those skilled in the art, it is possible to embody the invention in other forms than that shown, and the invention is not limited to a specific following of the details shown herein.

In the drawings:

Figure 1 is a view of a dye pole in position upon a conveyor;

Figure 2 is a cross-section on the line 2-2 of Figure 1;

Figure 3 is a fragmentary, longitudinal section on the line 3-3 of Figure 2;

Figure 4 is a cross-section through an end of the pole.

The dye pole is adapted to be supported upon any suitable form of conveyor, a fragment of one being shown in Figure 1, in which the conveyor chain is shown at 1 and the pockets or holders for the reception of the poles at 2.

The pole comprises a seamless steel tube 5 which is for the purpose of giving rigidity 70 and strength to the pole. The body of the pole is enclosed within a jacket 6 of hard rubber composition which is permanently vulcanized to the steel pole. A coating or film of cement 7 may be applied to the pole 75 before the hard rubber jacket is vulcanized in position, whereby the adhesion between the pole and the jacket will be assured.

At its central portion, over which the material to be dried is suspended, the pole is 80 formed with a plurality of flutes or grooves 10 which are separated by ribs 11. The material hanging over the poles is indicated at 12 and it will be apparent that as the material is supported upon the ribs, the grooves 85 or flutes will permit the liquid with which the material is saturated to drain out into the flutes. This is advantageous as it permits all of the material, both that in contact with the pole and that depending from 90 it, to drain.

The flutes extend along the entire portion of the pole upon which the material is suspended, but in order to prevent the liquid from draining to the ends of the poles and running onto the conveyor, the poles are formed with barriers, such as enlarged bulbed formations 15, at the ends of the flutes and somewhat larger than the ribs, so that the liquid is intercepted and will drain 95 off the enlargements 15.

These poles are roughly handled, being often dropped on their ends, and it is advisable to provide a different material at the ends of the poles than the brittle, hard 100 rubber which covers the body of the pole.

2
For this reason the ends of the poles are provided with plugs 16 which are made of a tough, but not brittle, rubber composition usually containing a large percentage of fibers and constitute cushions for the poles.

5 Each plug 16 is provided with a central projection 17 which enters the tube 5 for a sufficient distance to anchor the tube. In the manufacture of the dye pole, the plug 16 is usually formed in a separate operation, being given a partial vulcanization which sets it in its permanent shape. The projections 10 17, therefore, serve to support the tube 5 in the mold while the jacket 6 is being vulcanized about it, and so support and center the tube. In order to firmly unite the plug, a series of holes 18 are formed around the tube and rubber from the outer jacket will flow into these holes during vulcanization 15 and knit with the projection 17, thereby firmly anchoring the plug in position. The fibrous composition of the plug also prolongs the life of the dye pole and withstands the abrasion from the conveyor.

20 25 It will be observed that a highly satisfactory and efficient form of dye pole has been provided. The outer jacket of hard rubber will withstand acids and alkalies alike and will not discolor the most delicate 30 materials. It is easily kept clean and the fluted formation will materially aid in drawing off the liquid with which the material is saturated. It will withstand the hard usage and will not injure or cut the most delicate 35 threads. The steel tube in the center of the pole makes it rigid and it will not sag or warp.

What is claimed is:

40 1. A dye pole for use in drying materials such as yarns or artificial silks, comprising a steel tube, a hard rubber jacket surrounding the tube and vulcanized thereto, the outer surface of the jacket being provided with horizontal grooves, an enlarged formation at the end of said grooves, and a cushion plug at the end of the pole.

45 50 2. A pole for the uses and purposes set forth, comprising a rigid reenforcing member and a jacket of hard rubber permanently vulcanized to the reenforcing member.

55 3. A pole for the uses and purposes set forth, comprising a rigid reenforcing member and a jacket of hard rubber permanently vulcanized to the reenforcing member, the surface of the pole being formed with spaced longitudinal ribs to support the material spaced from the body of the pole.

40 4. A pole for the uses and purposes set forth, comprising a rigid reenforcing member centrally located in the pole, a jacket of hard rubber permanently vulcanized about the pole, and cushions secured in the ends of the pole.

45 50 5. A pole for the uses and purposes set forth, comprising a rigid reenforcing mem-

ber centrally located in the pole, a jacket of hard rubber about the pole, and cushion members of rubber composition located at the ends of the pole, the rubber being vulcanized permanently to the surface of the 70 reenforcing member.

6. A pole for the uses and purposes set forth, comprising a steel tube, a jacket of hard rubber surrounding the tube, and plugs of cushion rubber inserted within the ends 75 of the tube, the rubber being vulcanized permanently to the surface of the tube.

7. A dye pole having a hard rubber composition vulcanized to and amalgamated with its outer surface and a rigid reenforcing member extending longitudinally of the 80 pole.

8. A dye pole having a hard rubber composition vulcanized to and amalgamated with its outer surface and a rigid reenforcing member extending longitudinally of the 85 pole, the surface of the pole being grooved longitudinally for drainage purposes.

9. A dye pole having a hard rubber composition on its outer surface and a rigid reenforcing member extending longitudinally 90 of the pole, the surface of the pole being grooved longitudinally for drainage purposes, and barriers at the ends of the grooves to prevent liquid passing to the ends of the 95 pole.

10. A dye pole having an outer jacket of hard rubber, an inner core of metal to which the jacket is vulcanized, and plugs of cushion rubber at the ends of the pole.

100 11. A dye pole having an outer jacket of hard rubber, an inner core of metal to which the jacket is vulcanized, and plugs of cushion rubber at the ends of the pole, the surface of the pole being provided with longitudinal 105 grooves and spaced ribs to support the material and permit drainage thereof along the pole.

110 12. A dye pole having an outer jacket of hard rubber, an inner core of metal to which the jacket is vulcanized, plugs of cushion rubber at the ends of the pole, the surface of the pole being provided with longitudinal grooves and spaced ribs to support the material and permit drainage thereof along the 115 pole, and barriers at the ends of the grooves.

120 13. A pole comprising a centrally located rigid tube, a plug of cushion rubber having a projection entering the end of the tube, and a jacket of hard rubber surrounding the tube and vulcanized thereto and to the plugs.

125 14. A pole comprising a centrally located rigid tube, a plug of cushion rubber having a projection entering the end of the tube, a jacket of hard rubber surrounding the tube and vulcanized thereto, the tube being provided with holes, and inwardly extending projections from the jacket extending through the holes and vulcanized to the projections on the plug.

15. A pole for the uses and purposes set forth comprising a rigid reenforcing member centrally located in the pole, and a rubber covering surrounding the pole and enclosing the ends thereof, the said covering being permanently vulcanized to and amalgamated with the surface of the pole, that portion of the covering about the sides of the pole being of hard rubber composition and at the ends of the pole of more resilient composition. 15
16. A pole for the uses and purposes set forth comprising a rigid reenforcing member centrally located in the pole, and a rubber covering surrounding the pole and enclosing the ends thereof, the said covering being permanently vulcanized to and amalgamated with the surface of the pole.
